United States Patent Office.

WALTER PAYTON, OF LONDON, ENGLAND.

Letters Patent No. 73,830, dated January 28, 1868.

IMPROVED LATHE FOR TURNING IRREGULAR-CURVED FORMS.

The Schedule referred to in these Letters Patent and making part of the same.

TO ALL TO WHOM IT MAY CONCERN:

Be it known that I, WALTER PAYTON, of 70 Sewardstone Road, Victoria Park, in the county of Middlesex, England, have invented "Improvements in Apparatus for Cutting or Planing Curved Forms with progressively varying radii;" and I do hereby declare that the following is a full and exact description thereof, reference being had to the accompanying drawings, and to the letters of reference marked thereon.

My improvements relate to apparatus by which the correct cutting or planing of curved forms of progressively varying radii is facilitated, and when two of such forms are required to work together, by which their correct relative forms may be secured.

But that the invention may be fully understood, I will, by the aid of the accompanying drawings, proceed to describe means pursued by me in carrying the same into effect.

Description of the Drawings.

In order correctly to cut or form such vanes, I employ the following apparatus: The vanes of each axis are placed upon separate revolving bearings, between which is placed a slide-rest with supports for cutting-tools capable of adjustment. Upon each of these revolving bearings is applied a toothed wheel, formed with a projecting edge or rim, each of which is taken into by a separate click or driver; and each of these clicks or drivers is carried by a separate arm from a separate hollow axis, each carrying a toothed wheel. Each of these hollow axes encloses a revolving bearing, which bearings are geared together, and the teeth of one toothed wheel of each hollow axis gear into those of the other hollow axis, whilst the teeth of the other toothed wheel of each axis take into the teeth of racks in a reciprocating frame, in the to-and-fro motion of which an intermittent rotary motion is communicated to the rotary bearings, and the vanes carried thereby. Stops hold the parts of the revolving bearings during the return motion. This reciprocating frame has also applied to it an inclined bar, which is adjustable, and passes through or governs the motion of the support to the cutting-tools, to cause such support to travel to and fro in a transverse direction. The slide-rest is adjustable, and thus whilst one cutter is cutting that portion of a vane nearest its axis, another cutter is cutting the portion of another vane furthest from its axis, and progressively changing. The support to the cutters on this slide-rest is also capable of progressive motion across each vane.

Figure 1 shows a side view,

Figure 2 an end view, and

Figure 3 a longitudinal section of apparatus arranged to act according to the invention.

Figure 4 shows an opposite end view of the same apparatus, with some of the parts removed, in order that other of the parts may be more clearly seen.

Figure 5 is a transverse section.

Figures 6 and 7 are side and end views, showing some of the parts only.

In each of these figures the same letters are employed to indicate corresponding parts.

A is the table of the machine; A¹, supporting legs; B is the main or driving-axis, which is supported so as to revolve in the stationary bearings A², carried by the framing A. On this axis B is affixed the pulley B¹, with varying speeds, to receive a strap or band from a steam-engine or other suitable power. B² is a fly-wheel, also affixed to this axis to equalize its motion. On the opposite end of this axis B is affixed the plate C, with a dove-tail groove, C¹, to receive a sliding plate, C², capable of adjustment, as shown, in order to vary the extent of motion to the pin C⁴, carried by the plate C³, and the extent of motion imparted by that pin C⁴, and the connecting-rod D, to the arm E at each revolution of the axis-B. The connecting-rod D is connected to the arm E by a pin, D', and the arm E is affixed on a rocking-shaft, E¹, which is supported to make partial rotations, or rock in the bearings A³ carried by the plate A, and thence to give motion to the various parts, as will presently more clearly appear.

Suppose it be desired to cut or form truly two series of vanes to work together, then these axes with their vanes will be affixed on separate mandrels z z, and applied, one to one of the two axes F, and the other to the other of those axes F, in position to be acted upon by cutters G G, carried by the travelling-table H, and they are fixed on the ends of the axes F F in such manner that one cutter may commence to cut across the surface of

a vane, b' , of an axis affixed on a mandrel carried by one axis F at its smaller diameter, and progressively outwards, whilst the other cutter will act to cut across a vane, b' , of another axis affixed on a mandrel, z , carried by the end of the other axis F at its larger diameter, and progressively to its smaller diameter, and so on with each of them in pairs. For this purpose the axes F have progressive step by step rotary motion given to them, whilst the cutters have a corresponding motion given to them, in a direction to cut across the vanes to them, and fro, and a progressive sideway motion after each of such cross-cuts and previous to a fresh cut.

Motion to the axes F is obtained in the following manner: Upon the axis E' is affixed an arm, I , which by pin-joint I' is connected to the rod I^2 , which by pin-joint I^3 is connected to the slide I^4 , with capability of adjustment on, and of being fixed as required by the set-screw I^5 to the lever-arm I^6 . The lever-arm I^6 is fixed on the shaft I^7 , carried by the bearings I^8 , upon which shaft I^7 is also affixed the arm I^9 , which at its other end is by pin-joint I^{10} connected to one end of the connecting-rod I^{11} , the other end of which is by pin-joint I^{12} connected to one end of the lever-arm I^{13} , which turns freely upon the boss of the wheel J , and at its other end carries a click or driver, I^{14} , which takes into the teeth of the ratchet-wheel J affixed on the axis J^1 , which is supported so as to turn freely in fixed bearings carried by the standard A^4 from the table A. Upon this axis J^1 is also affixed a worm, J^2 , which takes into the worm-wheel J^3 affixed on the shaft J^4 . J^5 is a handle affixed to the axis J^1 , for the purpose of turning that axis J^1 , and parts connected therewith, in order that the parts generally may be readily brought into position for starting the machine, or otherwise.

In order to provide for wear and consequent looseness between the teeth of the wheels J^2 and J^3 , and to give facility for tightening in the event of such wear, the wheel J^3 is divided in the direction of the line J^* , fig. 1, into two parts, which are held correctly, with capability of adjustment in relation to each other by set-screws. In the event of any looseness, from wear or otherwise, between the teeth of these wheels J^2 and J^3 , by screws. K is turning one part of the wheel J^3 slightly on the other, any degree of tightening desired may be obtained. K is a click to take into the teeth of the ratchet-wheel J , and prevent back motion thereto. On the axis J^1 is affixed a click to take into the teeth of the ratchet-wheel J , and prevent back motion thereto. On the axis J^1 is affixed the plate J^5 with adjustable stud J^6 , capable of being shifted on that plate J^5 , and set as required. This stud J^6 receives one end of a connecting-rod, J^7 , the other end of which is received on to a pin, J^8 , carried by the plate J^9 , in order that a progressive vertical motion may be imparted to the plate J^9 , first in one direction and then in the opposite direction, in the step by step rotary motion of the plate J^9 . The plate J^9 is held in the vertical standard A^6 , but with capability of vertical motion therein. To the plate J^9 are also affixed two racks, L L. The teeth of one of these racks take into the teeth of a pinion, L^1 , affixed on the hollow shaft or axis L^2 , capable of revolving on one of the shafts F , and the teeth of the other rack, L , take into the teeth of a pinion, L^1 , affixed on the hollow shaft or axis L^2 , which is capable of revolving on the shaft or axis F . Upon each of these hollow shafts or axes is also affixed a toothed wheel, L^3 , the teeth of which take into each other. Upon each hollow shaft, L^2 , is also applied an arm, L^4 , carrying each a stud, L^5 , upon which is formed a click or driver, L^6 , and also a square block, L^7 , which is acted upon by a spring, L^8 , to keep the click in position. The outer ends of these clicks are capable of acting in recesses L^9 , formed for them in rims F^1 , formed respectively in the wheels F^2 affixed, one on each of the axes F , so as to impart a step by step rotary motion simultaneously to the two shafts F , and consequently to mandrels z and vanes b' , for the time applied at the ends of such axes or shafts F . L^9 are clicks, the end of each of which on the return motion of the clicks L^6 , passes into a recess, L^9 , to prevent back motion to the wheels F^2 . The to-and-fro motion is obtained to the cutters to enable them to cut across the vanes, by means of an arm, M , affixed to the axis E' , and rising up to between lugs on the under side of the slide H , which is capable of movement in guides N N , formed on or affixed to the plate N^1 , which is supported, with capability of transverse motion, between the V -guides N^2 N^3 , carried by the standard A^7 . This plate, N^1 , is formed to receive a pin, N^4 , from a plate, N^5 , which embraces the two edges of the inclined bar N^6 , carried by the plate J^9 , and which is capable of being set at different angles, and held by set-screws N^7 on the plate J^9 by which, in the step by step up or down motion of the plate J^9 , a step by step motion will be imparted to the plate N^1 and to the cutters G , in one or the other direction, depending upon the direction of motion for the time of the plate J^9 .

The table H carries the cutters G in the following manner: Upon the table H is applied the carrier G^* , which supports, with capability of movement, the tool-holders G^1 G^2 , carrying the cutters G . The tool-holders G^1 G^2 are formed with projecting heads G^3 G^4 , which, when the cutters G are being carried forward, come against the parts G^5 G^6 of the carrier G^* , and hold the cutters firmly in position, but after the cutters G have finished cutting, and are being carried backwards ready for a fresh cut, the tool-holders carrying the cutters G , allow of the cutters moving and passing freely over the work. These tool-holders G^1 G^2 , as shown, are formed cylindrical, and fit into correspondingly-formed openings in the carrier G^* , and at their ends, G^6 , are tapped to receive screws G^7 , carried by the wheels G^8 , by turning either one or both of which, in one or other direction, the tool-holders G^1 and G^2 , with their cutters G , will be drawn nearer to or further from each other, as may be required, in order to cut or plane vanes of larger or smaller diameters, or to adjust the position of one of the cutters in relation to the other. The screws G^7 are formed with square heads at the part where they are connected to the wheels G^8 , and they are held firmly in position by screws, and they are by preference cut left-handed, in order that when the tool-holders G^1 G^2 are caused to make a partial rotation, to allow of the cutters moving out of the way of the work in their backward motion, the tool-holders and the cutters carried by them may be drawn slightly inwards out of the way of that part of the work to be next cut or planed. The wheels G^8 are formed with notches or recesses G^9 , into which stops G^9 are pressed by springs G^{10} , in order to prevent those wheels, G^8 , revolving except when they are released by the attendant withdrawing the stops G^9 , by means of the handles G^{11} . G^{12} G^{13} are springs applied to the projecting heads G^3 G^4 , to bring back the cutters when they

have been moved out of position during their backward motion. $G^{13} G^{13}$ are recesses to receive screws for holding the carrier G^* correctly in position on the table H .

Figures 8, 9, 10, 11, 12, 13, 14, 15, 16, and 17, show the carrier G^* , and parts connected therewith, separately, full size.

The transverse motions of the cutters will be imparted simultaneously, with a partial rotation of the axes F , and the mandrel z acting for the time to carry vanes $b^1 b^1$, in order that after each motion of the cutters to or from the plate N across one of the vanes supported by each axis F , they may then move with these vanes a distance equal to that of a cut, so as to cut progressively the whole surface of each of those vanes. $O O$ are fixed standards with centres O^1 , adjustable by screws O^2 , to facilitate the correct setting and holding of the mandrels $z z$ on the ends of the axes $F F$.

Having thus described my invention, and means which I adopt in carrying the same into effect, I would have it understood that I do not confine myself to the precise details shown and described, as these may be varied without departing from the peculiar character of the invention; but

What I do claim, is—

1. The combination and arrangement of devices herein set forth, for cutting or planing curved forms, when operating in manner substantially as described.
2. Also I claim the axes $F F$ and $L^2 L^2$, when operated by rack and pinion $L L$ and clicks $L^6 L^8$, so as to give the desired progressive motions to the work to be cut or planed, or to retain such work stationary during the return motion of the cutters, in manner substantially as described.
3. Also I claim the arrangement of the cutters, so as to admit of their several adjustments and correct action in manner substantially as described.
4. And also I claim the method of imparting motion to the support N^1 of the cutting-tool or tools, by an adjustable arm, J^9 , and parts acting therewith, in manner substantially as described.

In testimony whereof, I have signed my name to this specification in the presence of two subscribing witnesses.

Witnesses:

WALTER PAYTON.
